US0D1037779S

(12) **United States Design Patent** (10) **Patent No.:** **US D1,037,779 S**
(45) **Date of Patent:** **** Aug. 6, 2024**

(54) **DRINKING CUP**

(71) Applicant: **Shanhang Yuan**, Guangdong (CN)

(72) Inventor: **Shanhang Yuan**, Guangdong (CN)

(**) Term: **15 Years**

(21) Appl. No.: **29/921,724**

(22) Filed: **Dec. 19, 2023**

(51) **LOC (14) Cl.** **07-01**

(52) **U.S. Cl.**

USPC **D7/509**; D7/514

(58) **Field of Classification Search**

USPC D7/509, 543, 300, 396.2, 507, 529, 524, D7/619.1, 622, 531, 532, 537, 704, 505, D7/213, 515, 523, 536, 530, 514;

D9/500, 549, 601; D3/202

CPC A63F 2009/0058; A47G 19/2205; A47J 41/00; B65D 21/02

(57) **CLAIM**

The ornamental design for a drinking cup, as shown and described.

DESCRIPTION

FIG. 1 is a top perspective view of a drinking cup showing my new design;

FIG. 2 is a bottom perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is bottom plan view thereof.

The broken lines depict portions of the drinking cup and form no part of the claimed design.

1 Claim, 8 Drawing Sheets
